ROOF COVERING

Filed Feb. 12, 1931

A diagram of a segmented rod. The rod is divided into several sections by vertical lines. The segments are labeled with the following measurements: 13, 14, 10, 20, 14, 21, 12, 21, 11, 12, and 21. The segments are shaded with different patterns: the first two segments (13 and 14) are white, the third segment (10) is hatched, the fourth segment (20) is cross-hatched, the fifth segment (14) is white, the sixth segment (21) is hatched, the seventh segment (12) is cross-hatched, the eighth segment (21) is white, the ninth segment (11) is hatched, the tenth segment (12) is cross-hatched, and the eleventh segment (21) is white. The label 'FIG. 6.' is written in the center of the diagram.

ROOF COVERING

Harry T. Nichols, Bridgeport, Conn.

Application February 12, 1931, Serial No. 515,203

9 Claims. (Cl. 108—7)

This invention relates to a roof covering, particularly to a covering composed of individual shingles, and has for an object to provide an improved shingle and arrangement of laying them which will give a better and more weather-tight covering at less cost both in material and in labor, and will also give a better appearance.

With the foregoing and other objects in view, the invention consists in certain novel features 10 of construction and arrangement which will be more fully disclosed in connection with the accompanying drawing.

In the drawing:

Fig. 1 is a top plan view of a roof covering 15 embodying my invention.

Fig. 2 is a vertical section substantially on line 2—2 of Fig. 1.

Fig. 3 is a horizontal section substantially on line 3—3 of Fig. 1.

Fig. 4 is a detailed section substantially on line 4—4 of Fig. 1 on an enlarged scale.

Fig. 5 is a similar section substantially on line 5—5 of Fig. 1.

Fig. 6 is a transverse section of the shingle on 25 a still larger scale showing its construction.

Fig. 7 is a similar section showing a slightly modified construction, and

Fig. 8 is a bottom plan view of a portion of a 30 strip of material showing how the shingles may be manufactured.

The individual shingles as shown are substantially rectangular in shape and may be of any size found desirable for manufacturing purposes, handling and the appearance when laid on the roof. A convenient size for most purposes is about 12" by 14", but as indicated they may of course be of other sizes if desired. They may also be made of various materials and either more or less flexible or rigid.

Individual shingles comprise a body portion 10 which is ordinarily preferably of substantially uniform thickness throughout the entire length and width of the shingle, and on its under side is provided a longitudinal center section 11 extending the entire length of the shingle, but of less width than the body portion so that the edges 12 are spaced inwardly from the side edges 13 of the body portion to thus provide an overhanging flange portion 14 on each side. This longitudinal strip or central under portion 11 is preferably of substantially the same thickness as the overhanging flange portion 14 so that the shingles will lie substantially flat when laid on the roof.

The shingles are laid substantially as shown in Figs. 1 to 3 in horizontal rows each higher row overlapping the shingles in the next lower row to give the proper covering and to expose the proper surface to the weather. The adjacent shingles in each horizontal row are widely

spaced, but less than the width of the individual shingle an amount approximately corresponding to the widths of the overhanging flange portions 14. Thus in Fig. 1 in which is shown a portion of a roof beginning at the eaves 15 there is laid on the foundation 16 a row of full sized shingles a with their flange portions 14 overlapping one-half shingles or filler members b of substantially the thickness of the center body portion 11 of the shingle. These short fillers b are used only 10 on the first or lower row to fill the space between the side edges of the portion 11 of the two shingles and support the flange portions 14.

Going now to the other rows it will be seen that any two adjacent shingles c in any horizontal row are spaced from each other laterally at a distance substantially equal to the width of the lower strip portion 11. In other words they are so spaced that their opposed vertical side edges 13 are spaced laterally from each other a 15 distance corresponding to the width of the central under portion 11 so that when the next higher row of shingles d are laid the central under portion or strip 11 will lie in between the vertical edges 13 of the shingles of the next 20 lower row, in this case the shingles c, and their flange portions 14 will overlap the vertical edges of the lower shingles and rest on the top surfaces thereof. Thus as the under strip or portion 11 is substantially the same thickness as 25 the body portion or the flange portions 14 it will rest on top of the shingles a in the second lower row, and will fill and seal substantially the entire space which would otherwise be formed between the side edges 13 of the two 30 shingles c and the lower edge of the shingle d as indicated at 17, and thus effectively seal this opening to prevent snow or moisture blowing or flowing upwardly under the shingles. With this arrangement less lap is required for 35 the upper shingles d for instance on the shingles a of the second lower row as will be seen in Fig. 1, this lap being indicated by the dotted line 18 which is the upper edge of the shingles a. It has been found that this lap need not be more 40 than about two or two and one-half inches. It will also be evident that with this construction of shingle the central or body portion between the edges 13 of the next lower shingles is supported by the lower strip 11 so that there is no 45 sagging at the central portion of the shingles and the top surface lies substantially flat throughout its length.

It will be evident that these shingles can be laid very rapidly because the spaced side edges 55 13 of the shingles in a row already laid provide perfect means for locating the next higher shingle, as all that is necessary is to place the next higher shingle with the lower central strip 11 seating between the edges 13 of the two spaced 60

shingles of the next lower row, and having the necessary overlap on the upper end thereof, and then by setting only two nails **19** the shingle is properly secured. Such a shingle and roof 5 have numerous advantages. It will be evident that it may be quickly and readily laid thus greatly reducing labor cost, and although it is only a single coverage roof it will be evident that the central portions of the shingles which 10 are the actual roof covering portions are substantially twice the usual thickness. Thus, the shingles lie flatter and hold their shape better, and when laid on an old shingle roof the outlines of these old shingles are not as apt to show 15 through as in the thinner shingles.

These shingles may be made of various materials but a very satisfactory material is to have the body portion **10** composed of a strip of felt saturated with asphaltum. The top surface of this strip is covered with crushed slate **20** of any desired color, and held to the surface of the felt by any suitable binder such as tar. The lower strip **11** may also be formed of tar, asphalt or other suitable binding material and 25 crushed slate, stone or other suitable surfacing material to the desired thickness, and especially its lower surface is covered with a layer of the crushed slate **20a**, leaving the under surfaces **21** of the overhanging flange portions **14** of the felt 30 uncovered. Thus when the shingles are laid as above described the asphaltum on the under surfaces **21** will seal itself to the adjacent upper surface of the lower shingles and thus make an effective waterproof joint. It will also be evident 35 that when the shingles are laid, practically the entire surfaces of the asphaltum saturated felt are enclosed so that evaporation of this asphaltum is reduced to a minimum and thus greatly prolong the life of the shingles. It will 40 also be evident that the central under portion or strip **11** not only supports the central body portion of the shingle so that there is no sagging of the central body portion and the shingle lies substantially flat, but the edges **12** of this central 45 portion are sealed against the edges **13** of the lower shingles, and the under surface of the portion **11** seals on to the top surface of the shingles **a** of the second lower row.

Such a shingle can also be manufactured in 50 large quantities at relatively low cost. This is illustrated in Fig. 8 wherein is shown a strip **22** of material for the body such as felt saturated with asphaltum. This strip shown is of a width corresponding to the width of two shingles, but 55 of course can be of the width corresponding to a single shingle or more than two shingles if desired. In the case of the double width strips as shown there is provided on the under surface thereof two strips **11** corresponding to the strips **11** of the shingles, and may be provided by suitable thicknesses of the binding material and crushed surfacing material. These strips are the width of the strips **11** of the shingles and are thus spaced laterally from the 60 side edges **23** and **24** of the strip **22** as indicated by **12** in Fig. 8, a distance corresponding to the width of the overhanging flange portions **14**. These two strips are spaced laterally from each 65 other a distance equal to the distance of twice the width of the flange portions **14**. Thus after applying these strips **11** to the strip **22** the strip can be cut longitudinally along the central line **25** halfway between the two strips **11** and also 70 cut transversely as indicated at **26** to thus make 75

the individual shingles without any waste of material.

As indicated the shingles may be made of different materials. Thus instead of forming the lower strip **11** entirely of crushed slate and a 5 binder such as tar this strip may be formed by means of a second strip **11a** as shown in Fig. 7 of felt saturated with asphaltum the same as the body portion **10**, and secured to the under side of the body portion by a binder or the asphaltum left on the surfaces of the members by the saturating operation. Then the lower surface of the strip may be covered with crushed slate held thereto by a suitable binder as shown at **27** Fig. 7. This strip is the same width as 10 the strip **11** of the first form, and has the same function of supporting the body of the shingle and of filling and sealing the space between the edges of two adjacent shingles in the next lower row.

Or if desired the shingle can be made of asbestos similar to the asbestos shingles now on the market. This shingle is usually quite rigid but would be molded in its center part of a thickness corresponding to the combined thickness of the body **10** and strip **11** as indicated at **28** Fig. 4, leaving the overhanging side flange portions **14** of substantially half this thickness and extending for the full length of the shingles. These shingles will be laid the same as 30 the shingles previously described.

It will be evident from the foregoing description that I have provided a shingle and roof covering which can be manufactured in large quantities at relatively low cost, which may be 35 laid rapidly with minimum labor as their construction indicates the proper place for laying each individual shingle, and all joints are effectively sealed. Also that the body portion is supported so that it cannot sag and lies substantially flat giving a very attractive roof. Further that although there is only a single coverage as far as the individual shingles are concerned, still this coverage is of substantially 40 twice the thickness of the ordinary single coverage roof, and the wastage in overlap is reduced to a minimum.

Throughout the specification I have described the use of crushed slate as a surfacing material but it will of course be understood that 50 other crushed stone or any other suitable surfacing material may be used, and therefore the term crushed slate is used in the specification and claims in a generic sense as meaning any of these materials.

Having thus set forth the nature of my invention, what I claim is:

1. A roof covering comprising shingles arranged in overlapping rows, each shingle comprising a body portion and a longitudinal central portion on its underside of substantially the thickness of the body portion and spaced at its opposite sides from the edges of the body portion, said shingles being laid with adjacent shingles in the same row widely spaced and with the central portion extending between the spaced side edges of the body portions of the shingles on the next lower row, said central portion on the under side of the body extending substantially the full length of the body and formed as an integral part of the body so that the body and this portion are mounted as a unit by the single operation of mounting the body.

2. A roof covering comprising shingles composed of a body portion and a longitudinal cen-

tral portion on the underside of the body portion spaced from the edges of the body portion providing longitudinal flange portions on the opposite sides of the shingle of less thickness than the central portion of the shingle, said shingles being laid in overlapping rows with the adjacent shingles of a row widely spaced with the central portion extending between the opposed side edges of adjacent shingles on the 5 next lower row and with the flange portions overlapping the vertical side edges of the lower shingles and resting on the top surfaces of these shingles, said central portion extending for substantially the full length of the shingle to prevent sagging of the central portion of the overlapping shingle.

3. A roof covering comprising shingles including a body portion of felt impregnated with asphaltum and the top surface covered with 10 crushed slate held thereto by a binder, a longitudinal central portion on the underside of the body portion of less width than the body portion to provide longitudinal flange portions at the opposite sides thereof uncovered on their 15 under surfaces so as to seal to the top surfaces of shingles under them, the shingles being arranged in longitudinal overlapping rows with the adjacent shingles of the rows widely spaced but less than the width of the shingle so that 20 the flange portions overlap the edges of two adjacent shingles of the lower row and rest on the top surfaces of these shingles and the central under portion extends between and fills the 25 space between the edges of these lower shingles.

35 4. A roof covering comprising substantially rectangular shingles comprising a body portion of felt saturated with asphaltum and covered with crushed slate on its top surface held with a binder, a longitudinal central strip on its under 30 surface comprising a binder and crushed slate, said strip being of substantially the thickness of the felt and of less width so that its longitudinal side edges are spaced from the side edges of the felt, leaving longitudinal projecting side portions 35 of felt, the shingles being arranged in horizontal overlapping rows with adjacent shingles in a row spaced apart a distance substantially the width of the central strip and with the shingles of one row located with its central strip filling the 40 space between the edges of two shingles of the next lower row and with the projecting portions of the felt resting on the tops of these shingles.

50 5. A rectangular shingle comprising a body portion of felt saturated with asphaltum, a longitudinal central portion on the under side thereof substantially the thickness of the body and spaced from the opposite side edges thereof leaving laterally extending portions of the body outwardly of the edges of the central portion, 55 and the top surface of the body and the under side of the central portion being covered with crushed slate held thereto by a binder leaving the under surfaces of the laterally extending portions uncovered.

55 6. In a roofing assembly a plurality of shingle elements, each comprising a flexible mineral surfaced asphalt coated fibrous layer forming a weather exposed surface and having a lower bituminous layer secured to the under side thereof and positioned inwardly from the edges running vertically of the eaves and extending substantially between the edges running parallel to the eaves, said lower layer having a thickness 60

that will substantially reach the underlying surface in assembly when said shingle elements are laid with said lower layer positioned between the spaces of adjacent elements of an adjacent course with the under side surfaces of the upper 5 layers of said shingle elements in contact with, the upper surface of said adjacent elements in said adjacent course.

7. A roof covering comprising a plurality of similar shingles composed of a body portion with 10 vertical side edges and an integral longitudinal central reinforcing portion on the under side of the body portion spaced from the edges of the body portion, providing longitudinal flange portions on the opposite sides of the shingle of 15 less thickness than the central portion of the shingle, said shingles being laid in overlapping rows with the adjacent shingles of a row widely spaced, with the central portion extending between the opposed vertical side edges of adjacent shingles on the next lower row and with the flange portions overlapping the vertical side edges of the lower shingles and resting on the top surfaces of these shingles, said central reinforcing portion extending for substantially the 20 full length of the shingle to support the central 25 portion thereof.

8. A roof covering comprising shingles including a body layer of composition roofing, comprising a base of flexible material and a top 30 surface covered with granulated particles held thereto by a binder, a longitudinal integral central layer secured on the under side of the body layer and of less width than the body layer to provide longitudinal flange portions at the opposite sides thereof uncovered on their under surfaces so as to engage the top surfaces of shingles under them, the shingles being arranged in longitudinal overlapping rows with the adjacent shingles of the rows widely spaced a 35 distance determined by the width of the central layer so that the flange portions of shingles of one row overlie the edges of two adjacent shingles of the next lower row and engage the granulated particles on the top surfaces of these shingles and the central portion of the overlying shingles extends for a substantial length of the shingle between and into the gap below the overlying shingle to thereby space the shingles and 40 support the body thereof.

50 9. In a roofing assembly a plurality of similar shingle elements each comprising a flexible mineral surfaced asphalt coated layer forming a weather exposed surface and having an integral spacing and reinforcing layer adjacent the under side thereof comprising a bituminous material, said spacing layer being positioned inwardly of the edges of the exposed layer running between the ridge and eaves of the roof and extending substantially between the edges running in the 55 direction of the eaves, and said shingles being laid in overlying rows with the corresponding face of adjacent shingles exposed to the weather and with the integral under layers of shingles of one row supporting their exposed layers and 60 spacing the adjacent shingles of the next lower row and projecting between said adjacent lower shingles with the under side surfaces of the exposed layers in contact with the upper surfaces of said adjacent lower shingles of said lower 65 row.

HARRY T. NICHOLS.
